RAIL SUPPORTING MEANS FOR SPINNING MACHINES

Edward Kinsella, Spondon, near Derby, England,
assignor to Celanese Corporation of America,
a corporation of Delaware

Application February 6, 1947, Serial No. 726,804
In Great Britain February 14, 1946

7 Claims. (Cl. 57—137)

1

This invention relates to textile machines and is particularly concerned with machines for the twisting and winding of yarns, such as ring spinning, flier spinning and cap spinning machines.

In machines of this type the spindles are generally arranged substantially vertically, and the traversing of the yarn being spun upon the bobbins or other yarn packages is effected by the vertical movements of a lifter rail, which carries either the bobbins on which yarn is being wound or guide means for conducting such yarn to the bobbins. The lifter rail is actuated by means of vertical rods known as poker rods which carry the lifter rail on their upper ends and are vertically reciprocated in guides or sliding bearings, each rod having a chain attached to its lower end, the chain passing over a flanged wheel or chain sprocket and being secured to a horizontally reciprocating traverse rod. In a long machine, having many spindles arranged in line, the lifter rail may be divided into sections each carried by two such poker rods appropriately spaced from one another along the length of the lifter rail section.

According to the present invention a twisting and winding machine for the collection of a series of yarns comprises a series of vertical spindles, a horizontal lifter rail adapted to be reciprocated vertically for traversing yarn upon bobbins mounted on said spindles and a plurality of vertical poker rods for carrying and actuating said lifter rail, said rods being disposed in pairs along the length of the lifter rail, the rods of each pair being disposed at substantially the same distance along the length of the rail, one attached near the front edge and the other near the rear edge of the rail. The arrangement of the poker rods in pairs in this way gives more even support to the lifter rail and reduces any tendency to the deflection or distortion thereof, without increase in the moving weight, each of the pair of rods employed having approximately half the weight of a single rod as employed heretofore in the same position along the length of the rail but disposed in the middle of its width. It also allows the vertical run of the chain by which the rods are operated to be located centrally between the two rods, being attached to the middle of a yoke by which the lower ends of the rods are connected; this relieves the poker rods of the bending moment arising in previous constructions in which the chain is connected to a small horizontal projection extending laterally from the bottom of each rod. In addition, the use of a pair of rods permits them to pass one on each side of the spindle rail instead of passing through a hole formed in the middle of

the spindle rail for the purpose as when a single rod is employed. The spindle rail is the rail, generally non-reciprocating, carrying the rotating bobbins in cases where the lifter rail carries the thread guide means as in a ring-and-traveller device, or carrying the thread guide means where the lifter rail carries the bobbins as in cap spinning machines.

For the guiding of the pairs of poker rods 10 poker rod slides or bearings must be provided, and the bearings of each pair must be parallel to each other within close limits in order that the poker rods may operate freely and accurately and without hesitation. The machining of the 15 bearings with the requisite degree of accurate parallelism is apt to be expensive. It has been found however that a less expensive mode of construction may be adopted by providing for some freedom of lateral movement for one of the 20 poker rods, the other being rigidly fixed at its upper and lower ends to the lifter rail and to the connection between the poker rods respectively. Thus the lower end of one poker rod may rest on an adjustable tappet passing through a yoke by 25 which the rods are connected while the upper end of the rod has a bearing surface on which the lifter rail rests, lateral movement of the upper end with respect to the rail being limited to means of a spring connection between it and the lifter rail.

While the invention is applicable to twisting and winding machines of the different types referred to above, it is of particular advantage as applied to ring spinning machines for the reason that the lifter rail of a ring spinning machine, having to accommodate in its width the diameter of a ring large enough to encircle a full bobbin, is generally made wider than a lifter rail in a cap spinning or flier spinning machine. In consequence the poker rods of each pair may be more widely spaced from one another and greater advantage is obtained in respect of the rigidity of the lifter rail.

In ring spinning machines, in which the yarn 45 fed to the bobbin passes from a balloon-guide or lappet guide disposed above the spindle to a traveller mounted on a ring which encircles the bobbin and is carried on the lifter rail, the thread forms a rapidly rotating balloon between the balloon-guide and the ring. On account of the rising and falling of the ring this balloon is not of constant height, and the amount of thread therein becomes shorter or longer as the ring is at the top or bottom of this traverse motion. This is apt to give rise 50 to undesirable tension variations in the yarn. Ac-

2

cordingly, means may be provided in conjunction with the traversing arrangement of the present invention for raising and lowering the balloon-guide in phase with the lifter rail so as to keep the balloon length constant or more nearly constant than if a stationary balloon-guide were employed. For this purpose the balloon-guides corresponding to the spindles of each section of lifter rail may be mounted on a common guide rail extending across and carried by the upper ends of two vertical rods slidably mounted in vertical bearings, and actuated by the same mechanism as the double poker rods described above. Thus, each vertical rod can be disposed close to one of the pairs of poker rods carrying the lifter rail and can be driven by a link and lever connection from the yoke joining the bottom ends of the poker rods. In order to deal with any slight lack of parallelism in the vertical rods, the section of rail carried thereby may be divided in the middle and joined by a flexible connection allowing slight play between the two parts.

By way of example, one form of ring-spinning machine in accordance with the present invention will now be described in greater detail with reference to the accompanying drawings in which:

Figure 1 is a sectional side elevation of the machine.

Figures 2 and 3 are details of the connections of the upper and lower ends, respectively, of the poker rods of the machine, and

Figure 4 is a front elevation of the machine.

The machine described is one that is particularly adapted for use in the collection by twisting and winding of a series of threads of artificial filaments continuously with their production. The machine comprises a series of vertical frames 6 on which is mounted a fixed horizontal spindle rail 7 carrying in suitable bearings and at equal intervals a series of rotatable spindles. For greater clarity in the showing of the remaining parts of the machine, the spindles and their bearings and driving arrangements, being of standard form, are omitted. The positions of the spindles are indicated by the showing in chain-dotted lines of the tops of the bobbins mounted thereon at 8.

The spindle rail 7 is of T section, the top of the T being vertical and facing the rear of the machine for attachment to the vertical frames 6, while the remaining limb is horizontal. The vertical frames 6 are spaced at intervals of five spindles. Behind and above the spindle rail 7 the vertical frames 6 carry a feed roller 9 adapted to be driven at constant speed, and to draw threads of continuous artificial filament indicated at 10 from a spinning cabinet (not shown) disposed behind and above the ring-spinning machine. The feed roller 9 supplies the threads 10 to the bobbins 8 so that the machine acts as a collecting device to receive the output of the spinning cabinet.

Beneath the spindle rail 7 is a fixed rail 11 of inverted channel section carrying, at alternate intervals of four and six spindles, vertical brackets 12 which support the spindle rail 7 between the vertical frames 6 and extend upwards beyond it as described hereafter. In bearings 13 in each bracket 12 is carried a combined roller and sprocket in the form of a wide roller 14 the middle section 15 of which is deeply recessed and formed with sprocket teeth rising from the bottom of the recess. On the unrecessed parts of the series of rollers ride two traverse rods 16 ex-

tending along the length of the machine and joined to one another by means of transverse yokes 19, one at a short distance from each roller 14. A chain 20 extends horizontally from each yoke 19 to the sprocket section 15 of the adjacent roller 14, from which it proceeds vertically downwards.

At the top and bottom respectively of each bracket 12 is a pair of sliding bearings 21, 22, 23, 24 adapted to receive two vertical poker rods 25, 26. The top front bearing 21 extends past the spindle rail 7 clear of the front edge thereof, while the top rear bearing 22 passes through a hole 27 in the horizontal part of the spindle rail 7 close to the vertical part thereof. The lower ends of the poker rods 25, 26 are joined by means of a horizontal yoke 28 rigidly attached to the rear poker rod 25 and carrying a screw 30 (Fig. 3) extending upwards through the other end, on which the lower end of the front poker rod 26 rests. The chain 20 referred to above is attached to the middle of the yoke 28.

Above the spindle rail 7 and supported by the upper ends of the pairs of poker rods 25, 26 is the ring rail 31, a flat rail with holes therein, one for each bobbin 8, large enough to accommodate a full package and carrying round the periphery of each hole a spinning ring 32 for the reception of the traveller 33. The ring rail is in sections each adapted to accommodate 10 bobbins 8 and each carried by two pairs of poker rods 25, 26, one pair disposed between the second and third bobbins and the other between the eighth and ninth bobbins of each group. The rear poker rod 25, which is rigidly attached to the yoke 28 at its lower end is rigidly attached at its upper end to the ring rail 31 also. The front poker rod 26 carries a domed mushroom-shaped bearing head 35 (Fig. 2) engaging in a recess 36 beneath the ring rail and centred in that recess by means of a helical spring 37 housed in the recess beneath the mushroom head, and secured on one end to the ring rail and at the other end to the poker rod 26.

Attached to the spindle rail 7 behind each pair of poker rods is a fixed bracket 40 the lower end of which reaches towards the rear of the machine and is bolted to a horizontal rail 41 connecting the vertical frames 6 of the machine. Close behind the spindle rail 7 each bracket is formed with upper and lower sliding bearings 42, 43 therein, one vertically above the other, for the reception of a balloon-guide actuating rod 44. On the upper ends of every two such actuating rods 44 is carried a horizontal balloon-guide rail 45 equal in length to the section of lifter rail 31 carried by the corresponding two pairs of poker rods 25, 26. Hinged to the balloon-guide rail 45 behind each bobbin 8 is a curved lever 46 carrying a thread guide 47 on its forward end to serve as a balloon-guide for that bobbin. The hinged lever 46 may be swung upwards and backwards as indicated in Fig. 1 to facilitate the replacement of a full package on the spindle by an empty package support.

The balloon-guide rail 45 is caused to rise and fall, through the balloon-guide actuating rods 44, by connections to the yokes 28 joining the corresponding pairs of poker rods 25, 26. Extending rearwards from the mid-point of each yoke is a lever, which is substantially horizontal in the mean position of the yoke 28, and is connected at its rear end by a substantially vertical link 51 to a pivot point on the lower part of 75 the bracket 40 where it is bolted to the horizontal

rail 41. The lower end of the balloon-guide actuating rod 44 is connected by means of a short link 52 to the mid point of the lever 50. In order to allow for any slight lack of parallelism between the two balloon-guide actuating rods 44, the balloon-guide rail 45 carried by them is divided at the middle into two parts which are held together by means of a flexible connection 53. By these means the balloon-guide 41 of each spindle is caused to rise and fall in phase with the ring rail 31, though for a shorter distance.

Having described my invention, what I desire to secure by Letters Patent is:

1. A twisting and winding machine for the collection of a series of yarns, said machine comprising a series of vertical spindles, a horizontal lifter rail adapted to be vertically reciprocated and to traverse the yarns upon bobbins mounted on said spindles, a plurality of vertical poker rods for carrying and actuating said lifter rail, and guide means embracing each poker rod along a substantial length thereof, through which guide means said poker rods are adapted to slide, said poker rods being disposed in pairs along the length of said lifter rail, the rods of each pair being at substantially the same distance along the length of the rail, one being attached rigidly near one edge of said lifter rail and the other attached flexibly near the other edge.

2. A twisting and winding machine for the collection of a series of yarns, said machine comprising a series of vertical spindles, a horizontal lifter rail adapted to be vertically reciprocated and to traverse the yarns upon bobbins mounted on said spindles, a plurality of vertical poker rods for carrying and actuating said lifter rail, guide means embracing each poker rod along a substantial length thereof, through which guide means said poker rods are adapted to slide, said poker rods being disposed in pairs along the length of said lifter rail, the rods of each pair being at substantially the same distance along the length of the rail, one being attached rigidly near one edge of said lifter rail and the other attached flexibly near the other edge, a horizontal yoke in association with each pair of poker rods, said yoke uniting the lower ends of said poker rods, and a chain connected to the mid-point of said yoke and extending vertically between said rods for actuating said lifter rail through said rods.

3. A twisting and winding machine for the collection of a series of yarns, said machine comprising a series of vertical spindles, a horizontal lifter rail adapted to be vertically reciprocated and to traverse the yarns upon bobbins mounted on said spindles, a plurality of vertical poker rods for carrying and actuating said lifter rail, guide means embracing each poker rod along a substantial length thereof, through which guide means said poker rods are adapted to slide, said poker rods being disposed in pairs along the length of said lifter rail, the rods of each pair being at substantially the same distance along the length of the rail, one being attached rigidly near one edge of said lifter rail and the other attached flexibly near the other edge, a horizontal yoke in association with each pair of poker rods, one end of said yoke being rigidly connected to the lower end of one of said rods, an adjusting screw extending upwards through the other end of said yoke on the end of which screw the other rod rests, and a chain connected to the mid-point of said yoke and extending vertically between said

rods for actuating said lifter rail through said rods.

4. A twisting and winding machine for the collection of a series of yarns, said machine comprising a series of vertical spindles, a horizontal lifter rail adapted to be vertically reciprocated and to traverse the yarns upon bobbins mounted on said spindles, a fixed rail extending beneath said lifter rail, a plurality of vertical poker rods for carrying and actuating said lifter rail, and guide means embracing each poker rod along a substantial length thereof, through which guide means said poker rods are adapted to slide, said poker rods being disposed in pairs along the length of said lifter rail, the rods of each pair being at substantially the same distance along the length of the rail and passing one on each side of said fixed rail, one being attached rigidly near one edge of said lifter rail and the other attached flexibly near the other edge.

5. A ring-spinning machine for the collection of a series of yarns, said machine comprising a spindle rail, a series of vertical spindles mounted on said spindle rail, a horizontal ring-rail adapted to be vertically reciprocated, a series of rings on said rail, each surrounding a spindle and carrying a traveller for traversing the yarns upon bobbins mounted on said spindles, a plurality of vertical poker rods for carrying and actuating said ring-rail, and guide means embracing each poker rod along a substantial length thereof, through which guide means said poker rods are adapted to slide, said poker rods being disposed in pairs along the length of said ring-rail, the rods of each pair being at substantially the same distance along the length of the ring-rail and passing one on each side of said spindle rail, one being attached rigidly near one edge of said ring-rail and the other attached flexibly near the other edge.

6. A ring-spinning machine for the collection of a series of yarns, said machine comprising a spindle rail, a series of vertical spindles mounted on said spindle rail, a horizontal ring-rail adapted to be vertically reciprocated, a series of rings on said rail, each surrounding a spindle and carrying a traveller for traversing the yarns upon bobbins mounted on said spindles, a plurality of vertical poker rods for carrying and actuating said ring-rail, guide means embracing each poker rod along a substantial length thereof, through which guide means said poker rods are adapted to slide, said poker rods being disposed in pairs along the length of said ring-rail, the rods of each pair being at substantially the same distance along the length of the ring-rail and passing one on each side of said spindle rail, one being attached rigidly near one edge of said ring-rail and the other attached flexibly near the other edge, a horizontal yoke in association with each pair of poker rods, said yoke uniting the lower ends of said poker rods, and a chain connected to the mid-point of said yoke and extending vertically between said rods for actuating said ring-rail through said rods.

7. A ring-spinning machine for the collection of a series of yarns, said machine comprising a spindle rail, a series of vertical spindles mounted on said spindle rail, a horizontal ring-rail adapted to be vertically reciprocated, a series of rings on said rail, each surrounding a spindle and carrying a traveller for traversing the yarns upon bobbins mounted on said spindles, a plurality of vertical poker rods for carrying and actuating said ring-rail, guide means embracing each poker

rod along a substantial length thereof, through which guide means said poker rods are adapted to slide, said poker rods being disposed in pairs along the length of said ring-rail, the rods of each pair being substantially the same distance along the length of the ring-rail and passing one on each side of said spindle rail, one being attached rigidly near one edge of said ring-rail and the other attached flexibly near the other edge, a horizontal yoke in association with each pair of poker rods, one end of said yoke being rigidly connected to the lower end of one of said rods, an adjusting screw extending upwards through the other end of said yoke on the end of which screw the other rod rests, and a chain connected to the mid-point of said yoke and extending vertically between said rods for actuating said ring-rail through said rods.
